(57) **CLAIM**

The ornamental design for a pinhole lens, as shown and described.

DESCRIPTION

FIG. 1 is a top, front, and right side isometric view of a pinhole lens showing my new design;

FIG. 2 is a bottom, rear, left side isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The portions of the figures shown in broken lines are not part of the claimed design.

1 Claim, 6 Drawing Sheets
